UNITED STATES PATENT OFFICE

2,472,305

POST PULLER

Charles E. Miller, Denver, Colo.

Application April 15, 1946, Serial No. 662,120

6 Claims. (Cl. 254—135)

1

This invention relates to means and devices employable in association with various forms and sources of power to pull, uproot, and removably break away from ground engagement posts, poles, shrubs, brush, small trees, and the like, to be displaced, and has as an object to provide a simple and convenient device for the transmission of applied power to effect such extractions.

A further object of the invention is to provide an improved facility adapted for convenient use by a single operator in the application of power to the displanting of ground-penetrating elements.

A further object of the invention is to provide an improved facility for the efficient direction of horizontally-applied power to substantially-vertically uprooting effect on elements to be displaced.

A further object of the invention is to provide an improved facility for the application of horizontally-directed power to and with enhanced elevating effect on elements to be displaced.

A further object of the invention is to provide an improved uprooting facility that is simple and inexpensive of manufacture, expeditious and convenient of use, efficient in attainment of the ends for which designed, and adapted for rugged, durable construction from readily-available materials.

With the foregoing and other objects in view, my invention consists in the construction, arrangement, and combination of elements herein-after set forth, pointed out in my claims, and illustrated by the accompanying drawing, in which—

Figure 1 is a side elevation of a typical embodiment of the improvement as positioned and arranged for practical use in the uprooting of a conventional fence post. Figure 2 is an elevation, on an enlarged scale, of and at right angles to the device of Figure 1. Figure 3 is a top plan view of the showing of Figure 2.

In the construction of the improvement as shown, the numeral 10 designates a straight, rigid, elongate strut formed from any strong, durable material, such as metal, in a size proportion and weight suited to the particular use for which the device is intended; said strut, for maximum strength and rigidity relative to its weight, conveniently being a tubular member such as a length of pipe, tubing, or the like. One end of the strut 10 abuts against and is rigidly and permanently secured, as by means of welding, to the web outer face midportion of a channel section 11 thereby fixedly associated with, perpendicular to, and in uniform extension outwardly from the sides of

2

said strut with the parallel channel flanges directed parallel to the axis and away from the adjacent end thereof. To enhance operative rigidity and permanence of the assembly, the outwardly-extending portions of the section 11 may be braced to the strut 10, as by means of gusset plates 12, or the like, secured to and filling the angles between adjacent strut 10 and section 11 portions. The end of the strut 10 remote from the channel section 11 is capped, plugged, or otherwise worked to fixedly mount, support, and position a notched plate or furcation 13 diametrically thereof in a plane paralleling the section 11 length with its centrally-disposed notch 14 opening axially and away from the adjacent end of said strut, said notch 14 being formed and sized to receive and engage about the central portion of a conventional chain link in a conventional manner operative to inhibit longitudinal displacement of the chain relative to the plate 13. At a convenient point along the strut 10, preferably midway between the section 11 and plate 13, a rigid bar 15 is fixed to said strut for projection on each side of the latter in parallelism with the section 11, and suitable braces 16 fixedly inter-connect between outer portions of said bar and said strut to reinforce and stiffen the mounting thus formed. The portions of the bar 15 projecting laterally beyond the strut 10 function as arms adapted to engage against and partially embrace the element to be uprooted to facilitate which purpose the bar 15 outer ends are desirably curved in the same direction away from the bar intermediate straight portion to form open hooks which serve in use to clip over one side of an element against which the bar 15 is engaged and hold the strut 10 closely adjacent the element other side.

In the actual use of the improvement for uprooting purposes, the base section 11 of the assembly is placed on the ground in suitably-spaced relation with the base of the element, such as a fence post 17, to be extracted, and the strut 10 is then tilted toward and past said element until one or the other of the bar 15 lateral extensions engages therewith. The arm of the bar 15 engaging the element holds the assembly from falling away therefrom, either forwardly or laterally, and frees the operator for further activities. A suitable chain 18 is wrapped and snubbed about the base of the element 17 and thence led upwardly over the upper end of the strut 10, one of the chain links engaging in the notch 14 of the plate 13, in a direction substantially perpendicular to the section 11 length and to connection with a source of power, such as a tractor, team of draft

animals, windlass, tackle, or the like, whereby strain tending to erect the strut may be applied to said chain. Obviously strain power-applied to the end of the chain 18 remote from the element 17 acts to tilt the strut to upright position about the line of section 11 engagement with the ground as a fulcrum, the bite of the channel flange against and into the ground serving to anchor the base of the assembly and thus prevent slipping, swinging the free end of the strut reversely past the element 17 and withdrawing the bar 15 from its contact with the element, during which arcuate travel of the strut 10 the chain length from the plate 13 to the element 17 base remains constant due to the chain link engagement within the notch 14 and the altitudinal rise of the strut upper end is made manifest as a powerful upward strain on said chain length tending to dislodge and elevate the element 17, the effective leverages involved materially augmenting the applied power. If necessary, successive lifts may be given to an element 17 through successive settings of the strut relative thereto, the point of strut engagement with the chain 18 being altered or the point of chain engagement with the element being readjusted as required, and the potency of the elevating force may be readily fitted to a given need, within an operatively extensive range, by variation of the angle between the strut initial placement and the vertical.

Since many changes, variations, and modifications in the specific form, construction, and arrangement of the elements shown and described may be had without departing from the spirit of my invention, I wish to be understood as being limited solely by the scope of the appended claims, rather than by any details of the illustrative showing and foregoing description.

I claim as my invention:

1. A post puller comprising a single rigid strut, a ground-engageable base on one end of said strut, a chain-engageable, notched plate on the other end of the strut to selectively receive links of a draft chain end-secured to a member to be uprooted and thereby determine the angular disposition and consequent leverage of said strut, and a post-engageable arm projecting laterally from an intermediate strut portion.

2. A post puller comprising a single rigid strut, a perpendicularly-related, ground-engageable base fixed to one end of said strut, a chain-engageable, notched plate fixed to and in axial projection with the other end of the strut to selectively receive links of a draft chain end-secured to a member to be uprooted and thereby determine the angular disposition and consequent leverage of said strut, and fixedly-related, oppositely-extending, post-engageable arms projecting laterally from an intermediate strut portion.

3. A post puller comprising a single rigid strut, a perpendicularly-related, ground-engageable base fixed to and for projection oppositely from one end of said strut, ground-gripping flanges

marginally along the under side of said base, a chain-engageable, notched plate fixedly projecting axially from the other end of the strut to selectively receive links of a draft chain end-secured to a member to be uprooted and thereby determine the angular disposition and consequent leverage of said strut, and fixedly-related, oppositely-extending, post-engageable arms projecting laterally from an intermediate strut portion in spaced parallelism with said base.

5. A post puller comprising a channel-section, ground-engageable base, a single rigid strut fixedly upstanding centrally from and perpendicular to the unchanneled web side of said base, a chain-engageable, notched plate fixedly projecting axially from the strut free end to selectively receive links of a draft chain end-secured to a member to be uprooted and thereby determine the angular disposition and consequent leverage of said strut, and fixedly-related, oppositely-extending, post-engageable arms projecting laterally from an intermediate strut portion in spaced parallelism with said base.

10. A post puller comprising a channel-section, ground-engageable base, a rigid strut fixedly upstanding centrally from and perpendicular to the unchanneled web side of said base, a chain-engageable, notched plate fixedly projecting axially from the strut free end, fixedly-related, oppositely-extending, post-engageable arms projecting laterally from an intermediate strut portion in spaced parallelism with said base, and angularly-offset arm free end portions adapted to partially embrace a post therewith associated.

15. A post puller having a rigid strut furnished with a perpendicularly-related, ground engageable base at one end and a chain-engageable, notched plate at its other end, means for non-slidably supporting said strut in inclined relation across and closely adjacent one side of a post to be uprooted, said means comprising ground-gripping flanges marginally along the said base under side, fixedly-related, oppositely-extending arms projecting laterally from an intermediate strut portion in spaced parallelism with said base for selective engagement against a post, and angularly-offset free end portions on said arms disposed to respectively partially embrace a post engaged by the associated arm.
